MACHINE FOR FOLDING THE MARGIN OF SHEET MATERIAL

Filed Feb. 5, 1935

UNITED STATES PATENT OFFICE

2,056,312

MACHINE FOR FOLDING THE MARGIN OF
SHEET MATERIAL

Robert Gow Reid, Jr., Leicester, England, assignor to United Shoe Machinery Corporation, Paterson, N. J., a corporation of New Jersey

Application February 5, 1935, Serial No. 5,146
In Great Britain May 1, 1934

17 Claims. (Cl. 270—93)

This invention relates to the folding of margins of sheet-material and is particularly, but by no means exclusively, concerned with folding parts of already cemented textile material in the production of waterproof clothing. In the manufacture of mackintoshes and similar clothing, it is often required to turn over the edges of such material to a distance of half an inch or more, the turned-over margin being secured by adhesive. The application of adhesive in a stripe of definitely controlled width is now commonly a machine-operation, instead of as heretofore a hand-operation, and particularly when adhesives which comprise a suspension of rubber in the form of prepared rubber latex are used, it is desirable to effect the folding operation by machine instead of by hand, as has been usual.

An object of the invention is to provide, in such a machine as that disclosed in the application of Robert G. Reid for improvements in folding machines, filed in the United States Patent Office on July 27, 1934 and bearing the Serial No. 737,246, for the effective and regular feeding of sheet-material without imparting a stretching action thereto, with a view to obtaining regular and flat marginal folding of material under all circumstances, and particularly when the material has been cut so that the margin to be folded is on the bias.

Another object of the invention is to guard against contact of the cemented margin with other portions of the material until the proper relation for adhesion has been attained, thus preventing incorrect folding and soiling of the material.

The above and other objects and the several features of the present invention will become apparent from a consideration of the following description, given by way of example and with reference to the accompanying drawing of a machine according to the invention.

In the drawing,

Fig. 1 is a front elevation of the head of the machine, with parts broken away;

Fig. 2 is a left-hand side elevation, partly in section, of the head shown in Fig. 1;

Fig. 3 is a sectional view of the work-edge-folding device, raised to receive the work; and

Fig. 4 is a view similar to Fig. 3, with the folding device in operating position.

The construction shown includes a frame 10 with two horizontal shafts 12 and 14 respectively journaled one above the other. The axis of the upper shaft 14 is slightly to one side of a vertical

plane through the axis of the shaft 12, as seen in Fig. 2. The shaft 12 is rotatable by power applied to a pulley 13, and carries at one end a knurled cylindrical roll 16, which projects slightly through a slot 18 in a horizontally disposed work-table 20 carried on the frame. The shaft 14 is connected by gearing 22 to the shaft 12 in such manner that a knurled cylindrical roll 24 carried at its end rotates at the same peripheral speed as the roll 16 and in the opposite direction. The shaft 14 is carried on a lever 26 pivotally movable about a spindle 28 and urged downwardly against an adjustable limit-stop 30 by a spring-pressed plunger 32 housed in the upper portion of the frame. The lever 26 has an arm 34, which is connected by a rod 36 to a treadle (not shown), by actuation of which the shaft 14 may be lifted bodily away from the shaft 12 raising the roll 24 for the reception of the work.

Mounted for vertical sliding movement upon the table 20 at the entering side of the rolls 16 and 24 is a drag-type work-pressing device or head 38, having a smooth under surface that overlies the edge of the table. The work-pressing device is held down in dragging contact with the folded margin of the work by a spring 40 and is provided with a laterally projecting pin carrying a roll 42, which is engaged by a manually operable cam-lever 44 pivoted on the table. The cam-lever has a notch 46 in its upper end into which, after being lifted by said lever, the roll 42 falls, so that the device 38 may be held up away from the table while the leading edge of a work-piece is being introduced between the rolls.

At the rear of the pressing device 38, or at the side from which the work advances, and mounted on a bar 48 under the work-table 20 to be movable horizontally towards and from the pressing device, is an adjustable edge-turning device 50. This turning device comprises a vertical plate 52 clamped by a screw 53 to a block 54. The block is slidable along the bar 48, and hinged to it is the edge-turning or folding device comprising a pair of parallel folding plates 56 and 58, which in operating position lie horizontally over the table. As shown in Fig. 2, the lower plate 58 extends rearwardly to a greater distance than the upper plate 56. The plates are so disposed as to enclose a slot-space 60 which receives the margin of the work-piece being folded. The width of said margin is adjustable by a gage 62 adjustably secured to the edge-turning device 50 by a headed screw 64, so that the gage 62

can be moved to leave more or less of the said slot-space 60 open. The folding device is movable about its hinge from its operating position over the work-table (Fig. 4), to one located conveniently for the introduction into the slot of the margin of a piece of material (Fig. 3), the device 50 with such margin being afterwards turned down together for the folding operation.

Were material drawn past folding and pressing devices of the nature above described solely by rolls, there might be a tendency to stretch and cause crinkling of the folded margin, this being particularly noticeable when material cut on the bias is thus fed through the machine. With a view to avoiding such a defect in folded material, a moving backing or supporting member which minimizes the frictional drag of the work against the table is employed. This moving supporting member conveniently takes the form of an endless conveyor-belt 66 of leather, rubber or the like, which passes over two guide-rolls 68 and 70 fixed one at either end of the work-table 20 and extends underneath the edge-turning device 50 and the work-pressing device 38 25 and between the two knurled rolls 16 and 24. The belt also passes under an idle pulley 72 mounted on a bracket 74 fixed to a rod 76 on the machine-frame 18 underneath the table, the pulley 72 being adjustable along a slot 78 in the bracket to take up slackness in the belt. Said belt may be caused to travel over the table by being gripped with the work between the two power-driven rolls 16 and 24, the knurling on which aids such movement.

In using a machine constructed as above described, a convenient procedure for the operator is to fold manually the leading corner of the margin of the material M, which margin has been coated with adhesive. This folded corner will be introduced between the rolls 16 and 24, which are at rest, it lying upon the belt 66. At this time, the pressing member 38 will have been lifted into its idle position by the cam-lever 44. The folding device 50 will have been turned back from its working position over the table (Fig. 3) ready for receiving the margin of the work-piece and positioned rearwardly along the edge of the belt as far from the pressing device as the guide-bar 48 allows. With the folding device thus located, application of the work to it will be facilitated. The operator will next pass the margin of the material into the slot 60 in the folding device, and will turn said device over into operating position (Fig. 4) and slide it up to the pressure device. The folded forward portion of the margin being thereby positioned properly under the pressure device, said device is allowed to drop upon the work. The machine is now started by throwing in the power-drive for the rolls, the rotation of which pulls the work and the belt forward together or from right to left as seen in Fig. 2.

Particularly when adhesive containing rubber is used, it is important that a cemented surface shall not be allowed to touch any other part of the material until it is in correct position to be caused to adhere permanently thereto, and, once contact is obtained, that air-bubbles shall not be surrounded by adhering surfaces. The threading of the cemented margin of a piece of material through an edge-turning device of the nature above described tends to maintain the marginally cemented portion apart from the other portions of the material, and it is not until they reach the pressing device that the cemented portions

are pressed into contact with one another. The pressing device acts over the full width of the cemented margin, and, as the material passes, it presses backwards any bubbles of air that may possibly be trapped in said margin. The rolls, besides acting to feed the belt and material through the machine, consolidate the two thicknesses of material already acted upon by the presser 38.

It is essential, as above described, that premature contact of a cemented surface and other parts of a piece of material be prevented, to avoid incorrect folding of the margin and soiling by adhesive, should contact of cemented and other surfaces occur and the surfaces be separated again to enable correct folding to be obtained. Also, if adhesive should be left on the material after separation, as above indicated, parts of the edge-turning device might pick up adhesive and still further put it where it is not wanted. To prevent such defects, the lower plate 58 of the two parallel plates, or that lying nearest to the table, is longer in the direction of work-feed than is the upper plate 56. This holds the upper portion of the marginal fold away from the lower until the two arrive at the folding point, at which they are brought into parallel relation, ready for pressing together. Secured by two screws 80 to the upper plate 56 is an arm 82, which extends outwardly beyond the hinged end of the plate. A stop member 84 is secured to the vertical plate 52 and rises above the table 20 at the side at which the turning device 50 is pivoted. The stop is so shaped that when the edge-turning device is in operating position, the outwardly extending portion of the arm 82 contacts with said stop member. This contact is arranged to occur when the parallel plates 56 and 58 are substantially horizontal and a space is left for the passage of the piece of material over the table and belt without the cemented surface touching the under side of the lower plate 58. It will be seen that by reason of the greater length of the lower plate as compared with the upper plate 56, premature contact of surfaces is rendered more unlikely, and should adhesive find its way on to the under surface of the plate 58, it is not likely to be transferred to material as it passes through the machine, because of the position in which said plate is held by the stop.

Having described my invention, what I claim as new and desire to be secured by Letters Patent of the United States is:

1. In a machine for folding the margin of sheet-material, means in engagement with which the material is advanced for turning the margin, supporting means traveling with the advancing material and upon which said material rests below the turning means, and pressure means having a work-engaging surface extending along the supporting means in the direction of travel and to which said supporting means delivers the material from the turning means.

2. In a machine for folding the margin of sheet-material, means in engagement with which the material is advanced for turning the margin, means traveling with the advancing material for supporting it at the turning means, and pressure means to which the supporting means delivers the material from the turning means, said pressure means acting upon the supporting means to cause its advance with the material.

3. In a machine for folding the margin of sheet-material, a traveling conveyor underlying

- and supporting the material, a turning device extending above the conveyor and operating upon the portion of the margin of said material directly above that resting upon the conveyor, a 5 drag-type pressure-head mounted to slide toward and from the conveyor and having a work-engaging surface extending along said conveyor to act upon the folded margin, and a spring arranged to urge the head toward the conveyor.
- 10 4. In a machine for folding the margin of sheet-material, a traveling conveyor engaging the material, a turning device extending above the conveyor and operating upon the margin of said material, and a plurality of pressure members 15 movable toward the conveyor and arranged to act successively upon the folded margin.
5. In a machine for folding the margin of sheet-material, a traveling conveyor engaging the material, a turning device extending above the conveyor and operating upon the margin of said material, and a plurality of pressure members movable toward the conveyor and arranged to act successively upon the folded margin, one of 20 said pressure members acting upon the conveyor 25 to effect its travel.
6. In a machine for folding the margin of sheet-material, a work-supporting table, a traveling conveyor passing over guide-rolls at the edges of the table and underlying the margin of the material, a turning device extending above the conveyor and operating upon the margin of said material, and opposite pressure members one of 30 which is movable toward and from the other, said members being arranged for respective engagement 35 with the conveyor and with the material.
7. In combination, a work-supporting table, a belt movable over the table supporting the margin of the work, margin-turning plates spaced from each other and extending over the belt, 40 and a drag pressure member movable above the table toward and from the belt to act upon the turned margin.
8. In combination, a table, a belt movable over the table, a guide member extending along the belt, margin-turning plates mounted to move 45 along the guide member, and a pressure member acting upon the turned margin.
9. In combination, a table, a belt movable over the table, a guide member extending along the belt, a slide movable upon the guide member, and margin-turning plates pivoted upon the slide for movement toward and from the belt.
- 50 10. In combination, a table, a belt the upper run of which is dragged over the table, a margin-turning device mounted near the table to extend over the belt, and a pair of pressure-rolls between which the belt carrying the turned margin passes, one of said rolls being driven.
- 55 11. In combination, a table, a belt one run of which rests upon and is movable over the table, a margin-turning device mounted near the table to extend over the belt, a drag pressure member
- positioned to rest upon the folded margin and spring pressed toward the upper side of the table, and means to pull the work and the belt together under the pressure member.
12. In combination, a table, a belt movable over 5 the table, a margin-turning device mounted near the table to extend over the belt, a pressure-head movable above the belt into engagement with the turned margin of a piece of work, and a pair of pressure-rolls between which the belt and turned 10 margin pass.
13. In a machine for folding the margin of sheet-material, a table over which the material is advanced for the turning of the margin, a margin-turning device pivoted at one side of the 15 table to move toward and from said table, and a stop member secured adjacent to the pivot and limiting the movement of the turning device toward said table.
14. In combination, a table, a belt movable over 20 the table, a guide member extending along the belt, a slide movable upon the guide member, margin-turning plates pivoted upon the slide for movement toward and from the belt, and a stop member secured to the slide and limiting the 25 movement of the turning plates toward the belt.
15. In a machine for folding the margin of sheet-material, a table over which the material is advanced for the turning of the margin, a pair 30 of margin-turning plates spaced from each other above the table to receive the margin between them, said plates being pivoted at one side of the table, and a stop member rising above the table at the side to which the plates are pivoted, said plates having a projection contacting with the 35 stop member in the operating position of the plates.
16. In a machine for folding the margin of sheet-material, a table over which the material is advanced for the turning of the margin, and 40 a pair of margin-turning plates spaced from each other above the table to receive the margin between them, the plate lying nearest the table extending rearwardly with respect to the direction of advance of the material a greater distance 45 than the companion plate.
17. In a machine for folding the margin of sheet-material, a table over which the material is advanced for the turning of the margin, a pair 50 of margin-turning plates spaced from each other above the table to receive the margin between them, the plate lying nearest the table extending rearwardly with respect to the direction of advance of the material a greater distance than the companion plate, said plates being pivoted at one 55 side of the table, and a stop member rising above the table at the side to which the plates are pivoted, said plates having a projection contacting with the stop member in the operating position of the plates.

60 ROBERT GOW REID, JR.
